TIMING MECHANISM FOR AUTOMATIC FOLDERS

Harry D. Abell and Homer E. Abell,
St. Albans, Vt.

Application January 25, 1946, Serial No. 643,439

5 Claims. (Cl. 270—84)

1

This invention relates to an automatic folding machine and more particularly to an automatic folder for all flat work passing through a laundry ironer; especially to such machines as are of the type having measuring mechanisms operating on the flat work and controlling the operation of the folding mechanism.

One object of the invention is to provide folder controlling mechanism sufficiently compact to allow for its location between the conveying tapes, whereby a unitary machine may be compactly constructed with a plurality of lanes each having a plurality of folding and controlling mechanisms. A further object is to improve the driving and clutching mechanism which controls the operation of the folders.

Another object of the invention is to provide a machine that is simple in construction, easy to operate, of economical manufacturing cost and inexpensive in maintenance thereof.

With the above and other objects and advantages in view, the invention consists of the novel details of construction, arrangement and combination of parts more fully hereinafter described, claimed and illustrated in the accompanying drawings in which:

Figure 1 is a side elevation of an embodiment of the invention;

Figure 2 is a top plan view of the folding and control mechanism as applied to the machine;

Figure 3 is a sectional view thereof on the line 3—3 of Figure 2;

Figure 4 is an enlarged view of the control mechanism;

Figure 5 is a sectional view on the line 5—5 of Figure 4;

Figure 6 is a sectional view on the line 6—6 of Figure 5;

Figure 7 is a sectional view looking in the opposite direction to that of Figure 6;

Figure 8 is a front view of the control mechanism partly broken away showing the mechanism in normal position;

Figure 9 is the same showing the mechanism in operative position;

Figure 10 is an enlarged view of the idler disc of the folding mechanism of the control unit;

Figure 11 is an enlarged view of a control arm of the equalizing section of the control unit and

Figure 12 is a sectional view on the line 12—12 of Figure 11.

Referring more in detail to the drawing the reference numeral 20 generally designates the machine embodying the invention, which comprises the base section 22, front top section 24 and rear

2

top section 26. The sections are secured together in unit assembly by means of bolts or any type of well known fastening means.

Journalled transversely of the base section 22 in bearings 28 are the aligned shafts 30 and 32 on which are mounted rollers 34 over which are trained the plurality of carrier tapes 36. Also journalled transversely of the base section 22 in bearings 36' are the aligned shafts 38 and 40 on which are mounted rollers 42 over which are trained the plurality of carrier tapes 44. The tapes 36 are in parallel relation to the tapes 44 but spaced therefrom.

Journalled transversely of the front top section 24 in bearings 46 are the shafts 48, 50, 52, 54, 56, 58 and 60 and brackets 62 mounted on the front of the section 24 adjustably mount the arms 64 thereon. The arms 64 extend forwardly of the section 24 and the adjustment of the arms are accomplished by means of the opposed notches 66 coacting with the bolts 68 in the brackets 62. A shaft 70 fixed at the outer ends of the arms 64 rotatably mounts a roller 72 transversely thereof and a plurality of carrier tapes 74 are trained over the rollers 76 on the shafts 48, 50, 52, 54, 56, 58 and 60 and roller 72. Also journalled transversely of the front section 24 in bearings 78 are the shafts 80 and 82 on which are mounted rollers 84. A second set of carrier tapes 86 are trained over rollers 76 on shafts 48, 50, 52 and 56 in parallel contacting relation with tapes 74. The carrier tapes 86 are also trained over the rollers 84 on shafts 80 and 82.

The set of tapes 74 form a receiving table upon which the flat work is placed by the operator, and carry the work upwardly in cooperation with the tapes 86. The goods pass around shaft 50, then around shafts 52 and 54, and then move downwardly past the roll 76 on shaft 56. At this point the tapes 74 and 86 separate, the former passing downwardly around shaft 58 and the latter upwardly around shaft 80. The goods hang down freely in front of a folder blade carrier 132 operated by a control mechanism 154 (Fig. 3), the construction of which will appear later. As shown in Fig. 2, the folder actually consists of a plurality of blades 146 passing through the spaces between adjacent tapes of the set 74. The goods are prevented from reaching the floor by the tapes 44.

Journalled transversely of the rear top section 26 in bearings 88 are the shafts 90, 92, 94, 96 and 98 on which are mounted rollers 100. A plurality of carrier tapes 102 are trained over the rollers 100 on the shafts 96, 94, 96 and 98, and under the roller 100 on the shaft 92. Also journalled trans-

versely of the rear top section 26 in bearings 104 are the shafts 106, 108, 110, 112 and 114 on which are mounted rollers 116. A second set of carrier tapes 118 are trained over the rollers 116 on the shafts 106, 108, 110 and 112 and under roller 116 on shaft 110 and over rollers 100 on shafts 96, 94 and under roller 100 on the shaft 92 in parallel contacting relation with tapes 102. Also journalled transversely of the section 26 in alignment with shaft 114 in bearings 120 is the shaft 122 having the roller 124 mounted thereon. The delivering tapes 126 are trained over the roller 124 on the shaft 122 and the roller 116 on the shaft 114.

The sets of tapes 102 and 118 come together between the shafts 90 and 106 in front of the folder blade mounted on carrier 132. As the blade is advanced it carries the goods between the two tapes 102 and 118. The goods are thus folded and are carried away by the tapes upwardly on an inclined path, around shafts 94 and 96, and finally downwardly in front of a folder operated by a second control mechanism 154. The blade of this second folder carries the goods into the bite of tapes 118 (which left tapes 102 as they passed around shaft 96) and 126. These tapes cause the second fold to be formed and discharge the doubly folded goods from the machine. If but one fold is to be made the second folder can be made inoperative, in which case the singly folded goods are discharged from between tapes 102 and 118 upon the upper run of tapes 36.

Mounted transversely on each of the sections 24 and 26 is an angle iron bar 128 on which are mounted spaced roller brackets 130 which function as upper guide rollers for the rods 132. The rods 132 extend at right angles to the bar 128 and at their ends are connected to the angle iron bar 134 which is movable relative to the section in parallel relation with the bar 128. A second bar 136 parallel to bars 128 and 134 and in spaced relation to bar 128 is also mounted transversely of the section. Spaced roller brackets 137 are secured to the bar 136 in a position to act as lower guide rollers for the rods 132. The ends of the bars 128 and 136 are secured to angle bars 138 which in turn are secured by fasteners 140 to the section at right angles to bars 128, 134 and 136. The bars 138 act as a track or guideway for the bar 134.

Secured to the upwardly disposed flange 142 of the bar 134 by fasteners 144 are the forwardly extending fingers 146 referred to above as passing through the spaces between adjacent tapes of the sets 102 and 118.

The inner rods 132 are bridged at their outer ends by a bar 148 and a coupling 150 at the center of the bar 148 is connected to a cable 152 which enters the control mechanism 154 mounted on the angle iron bar 156.

A stud 170 secured to the top of the housing 158 on the wall 164 receives one end of a coil spring 172, the other end of which is connected to a stud 174 on the bar 134 thereby tensioning the bar 134 as will be later explained.

The control mechanism 154 has a double function, in general similar to that of conventional folding controllers, one being the measurement of the goods to determine the midpoint and the other the activation of the folder at the exact time that the midpoint comes into position to be folded. The control mechanism is set in operation by a trip 268 to be described below, which is depressed by the passage of the front end and released by the passage of the rear end of the

goods. Depression of the trip starts in motion the travel of a control arm within mechanism 154 at a speed proportional to half the speed of the goods. Release of the trip transfers the arm to a speed having the same ratio to the full speed of the goods. When this occurs the arm has been set, by its half speed motion, at a position corresponding to the midpoint of the goods. As full speed motion continues the arm reaches a position where it sets in motion the operation of the folder just as the midpoint of the goods arrives opposite it. In general, mechanisms operating on this basic principle are well known, and the features in which the present invention is an improvement thereon will appear below.

The control mechanism 154 comprises a housing 158 having sides 160 and 162 and a peripheral wall 164 held within a rabbet 166 in each of the walls. The side walls are flanged at 168 for attachment to the bar 156. Journalled at 176 in the side walls are parallel shafts 178 and 180. The former of these is the drive shaft, receiving motion from any desired source so that its speed is in a constant proportion to that of the conveying tapes. A gear 182 keyed to shaft 178 drives a gear 184 keyed to shaft 180 through an idler gear 186 mounted on a stub axle 188.

The driving cable 152 for operating the folder enters the housing 158 through opening 190 and is connected by a fastener 194 to the rim 193 of the idler disc or member 192. The disc 192 is loosely mounted on the shaft 178. The arm 196 of the member 192 has a spring pressed ratchet pawl 198 mounted thereon by the bolt 200 and the pawl is adapted to engage a ratchet gear 202 keyed to the constantly rotating shaft 178. A spring 316 on the pawl 198 is positioned so as to lie in the path of an arm 220 (Figs. 11 and 12), free on shaft 180, when the arm has been carried directly under it by mechanism to be described. When this happens the pawl is caused to engage the constantly rotating ratchet 202 and the idler disc 192 turned in a direction to wind up the cable 152. This pull on the cable moves the folder 45 into the bite of the conveying tapes to form a fold in the work.

The mechanism for actuating the arms 220 will now be described. As is customary in this type of mechanism a plurality of arms 220 (here indicated as two) are provided in order that an arm may always be ready at the starting point. Were this not done the folder would be unable to handle closely spaced small articles. This being a common expedient the operation of the machine will be described without more than passing reference to more than one of the arms. Keyed to the shaft 180 interiorly of the housing 158 is the ratchet disc 204 which is provided on one side thereof with a bevel gear 206. A paralleling 60 related and companion, although stationary, bevel gear 208 is formed on the inner surface of the side 162. A disc 210 having a marginal flange 212 extending in the same plane as the disc 204 is loosely mounted on the shaft 180. The disc 210 65 is driven by a bevel pinion 214 mounted on a stub shaft 216 in bearings 218 formed on the disc and meshing with bevel gears 206 and 208. As the former is driven it will roll the pinion 214 around the stationary gear 208 at half the speed of gear 70 206. The disc will of course also travel at this half rate.

Loosely mounted on the shaft 180 in contact with the disc 204 are the arms 220 which may be two as shown or more if desired. The arms 75 220 are curved outwardly at 222 to form a bearing

for pivotally mounting a dog 224. The dog has at one side of its pivot a tail 330 and at the other a pawl 331 adapted to engage the ratchet 204 if the tail of the pawl is moved outwardly. The pawl 331 is pressed towards the ratchet by a spring 226 compressed between an abutment 332 on the dog and a friction member 228. The latter has an angular friction surface 333 which engages the inside of rim 212 and side wings 334 which overlie the bearing section 222 of the arm 228 so that the friction piece and the arm move together in rotation. The friction member is thus free radially of the arm so that it may be at all times yieldingly pressed by spring 226 against the constantly rotating half speed rim 212. If the tail 330 is pressed downwardly as viewed in Fig. 12 the pawl 331 will be raised clear of the ratchet 204 and the arm will be driven by the half speed disc 210 through the friction member. If the tail 330 is released the spring 226 will shift the pawl 331 into engagement with ratchet 204 and the arm will be positively driven at full speed with the friction member sliding along the half speed rim. It will be noted that the spring is compressed as the pawl is withdrawn from the ratchet, so that under half speed conditions the friction drive is quite positive in operation.

A disc 232 is loosely mounted on the shaft 180 and acts as a spacer for balls 233 adapted to seat in conical shaped recesses 249 in the side wall 160. If the disc is rotated slightly, as it is periodically by the cord 266 attached to trip 268, the balls will be rolled out of the recesses 249, converting the pull on the cord into axial movement of certain parts in the control housing, as will now be described.

A live or movable rail, or flange member, 234 is loosely mounted on shaft 180 so as to be capable of movement along the shaft. This motion is permitted, and rotation prevented, by headed studs 335 (Fig. 7) passing through holes in the member 234 and through arcuate slots 336 in the disc 232. A spring 233 surrounds the shaft and presses against member 234 to hold it against the balls 233. Since the spring presses at its other end against the arms 220 it also keeps them in position relative to the disc 204.

The flange member 234 extends for three fourths of the circumference thereof and the remaining quarter is cut out to mount the convex concave flanged member 244. The member 244 is secured to side wall 160 through a slot in disc 232 by fasteners 246 and is spaced from the side wall by bushings 248. The convex edge of the member 244 is spaced from the flanged member 234 as shown at 250 and a release dog 252 is pivotally mounted on the member 234 adjacent the edge of the member 244 by a pin 254.

Secured to the disc 232 at right angles thereto and extending through the opening 256 in the side wall 160 is a lug 252. One end of a spring 260 is connected to the lug 258 by the fastener 262 and the other end of the spring is connected to the side wall 160 by the fastener 264. A cable 266 is connected to the lug 258 at one end and at the other end to a trip consisting of a bell crank lever 268 which is pivotally mounted in the slot 270 in the bracket 272 secured to the section 24 adjacent to and coacting with the carrier tapes 74 and 86. The control housing and the associated parts previously described are retained in assembled position by bolts 271. When the leading end of a piece of flat goods between the tapes depresses the trip 268 the resulting pull on cable 266 rotates the disc 232 enough to roll the balls 233 out of de-

pressions 249. The live rail 234 is thereby pushed into line with the rail 244 and will remain in that position as long as the goods are passing over the trip. Prior to activation of the trip an arm 220 has been held on the rail 244 by the escapement 252, as shown in Fig. 8. Depression of the trip, through the resultant rotation of disc 232, shifts the escapement to the position of Fig. 9, in which one arm 220 has been released and a second following one is held back. When the escapement is returned to its first position control of this second arm will be transferred from the rear to the forward arm of the escapement. When the goods pass the trip the pull on the cable is relaxed and disc 232 is returned by spring 260 to allow the balls to drop into the recesses and the live rail 234 to return to its inactive position of Fig. 8. This movement of rail 234 carries it beyond the tail 330 of dog 224, releasing the latter so that the spring 226 will cause engagement of the pawl 331 with the ratchet 204. The dog and its arm 220 thereupon move at full speed, finally passing pawl 198 and pressing it into engagement with the ratchet 202. Further movement of the arm carries the tail 330 under the flared end of rail 244, which depresses the tail and removes pawl 331 from the ratchet 204. The arm is ultimately brought to rest by striking either the escapement 252 or other arms 220 resting against it.

As shown in Figure 1 there are two control mechanisms used and since the construction of one is similar to the construction of the other it is believed that the foregoing description will be sufficient; the only difference being the location of the second control mechanism which is so positioned that the lever 268 will coact with the carrier tapes 102 and 118 and the cable 266 is trained over pulley 273. The second folder and its control mechanism operate exactly like the first to fold on its median line the piece of goods passing it. Since the piece of goods has once before been folded on its median line the second fold is on the quarter and three quarter lines of the original unfolded piece.

A shaft 274 mounted transversely of the base section 22 is provided with a sprocket for a chain drive 278 to a power operating mechanism, not shown. A sprocket 280 also on the shaft 274 is adapted for a chain drive connection 282 with a sprocket on shaft 30. The chain 282 also engages a sprocket on shaft 40. A sprocket 288 on shaft 38 has driving connection by means of the chain 290 with a sprocket 292 on the shaft 294, a sprocket 296 on the shaft 58 and a sprocket 298 on shaft 56.

Shaft 30 is provided with a second sprocket 300 having a chain drive connection 302 with the sprocket 304 on the shaft 112, the sprocket 306 on the shaft 338, the sprocket 310 on the shaft 116 and the sprocket 312 on the shaft 96. Thus rotation is provided for the rollers and carrier tapes of the folding machine.

The material to be folded is fed over tapes 74 and 86, over the trip 268 and eventually in front of folder 246. As the front of the material depresses the trip an arm 220 is released for motion at half speed, which is changed to full speed when the passage of the rear of the material releases the trip. The arm has, during the half speed period, traveled a distance having a predetermined ratio to half the length of the material, and thereafter moves at a speed having the same ratio to the full speed of the material. The folder and the tripping spring 316 of pawl 198 are set so that the mid-

point of the piece arrives at the folder just as the latter forces the material between the tapes. The midpoint of the piece is always registered with the arm 220 at the time the material runs off the trip, so that irrespective of the actual length of any piece of material it will always be folded at its midpoint. A second fold at the quarter point may if desired be made in the same way by the second folder.

Having thus described the invention what is claimed as new and desired to be secured by Letters Patent is:

1. Timing mechanism for controlling the folding blade of a machine for folding a piece of sheet material at its midpoint, said machine being of the type in which a folding blade is actuatable by passage of a rotating arm past a fixed point, said arm being driven at one speed during the passage of the work past a fixed point and at double that speed thereafter; said timing mechanism comprising an arm pivoted for rotation about an axis, a member rotatable on said axis and having an annular friction surface adjacent the arm, means for rotating said member continuously, a friction pad carried by the arm, a ratchet mounted within the annular friction surface, means for rotating the member at half the angular speed of the ratchet, a lever transversely pivoted on the arm, having a tail projecting at one side of the arm, and a pawl projecting at the other, a spring holding the pad continuously against the annular friction surface and pressing the pawl towards the ratchet, a movable abutment coaxial with the arm and engaging the tail of the lever to hold the pawl out of engagement with the ratchet, a stationary abutment having a cam surface inclined in a direction to shift the tail of the lever into position to be engaged by said abutment, and work-controlled means to remove the abutment from contact with the tail of the lever to permit the pawl to move into contact with the ratchet.

2. Timing mechanism as claimed in claim 1 in which the movable abutment is formed as a disk with a segmental annular flange coaxial with the arm and receiving the tail of the lever within it, said disk being shiftable by the work-controlled means axially away from the arm and out of contact with the tail of the lever, and a fixed segmental rail substantially completing the circle of the segmental flange and having an outwardly flaring entrance end to engage the tail of the lever and withdraw the pawl from contact with the ratchet.

3. Timing mechanism as claimed in claim 1 in which the work-controlled means includes a plate rotatable about said axis, a stationary member adjacent the plate, balls carried in openings in the plate, normally seated in depressions in the stationary member and in engagement with said abutment, a work-controlled feeler, and means connecting the feeler and the plate to rotate the latter to cause the balls to ride out of the depressions and shift the abutment in a direction to engage the tail of the lever.

4. Timing mechanism for controlling the folding blade of a machine for folding a piece of sheet material at its midpoint, said machine

being of the type in which a folding blade is actuatable by passage of a rotating arm past a fixed point, said arm being driven at one speed during the passage of the work past a fixed point and at double that speed thereafter; said timing mechanism comprising a closed casing, a pair of parallel shafts journaled in the casing, at least one arm pivoted for rotation about a first of said shafts, a member rotatable on said first shaft and having an annular friction surface adjacent the arm, a friction pad carried by the arm, a ratchet secured to the first shaft within the annular friction surface, gearing for rotating the member at half the angular speed of the ratchet, a lever transversely pivoted on the arm, having a tail projecting at one side of the arm and a pawl projecting at the other, a spring holding the pad continuously against the friction surface and pressing the pawl towards the ratchet, a flanged disk movable axially on said first shaft and engaging the tail of the lever to hold the pawl out of engagement with the ratchet, work-controlled means connected with said disk to shift it on the shaft away from said arm to release the tail of the lever and permit the pawl to engage the ratchet, a stationary flanged member having a cam surface inclined in a direction to shift the tail of the lever into position to be engaged within the flange of said flanged disk, means for rotating the second shaft, a second ratchet secured to the second shaft, a second disk rotatable on the second shaft, a pawl carried by the second disk in position to be shifted into engagement with the ratchet by engagement with it of the arm on the first shaft, folder operating means connected to said second disk, and a stop for disengaging the pawl from said second disk when the disk has rotated a predetermined amount.

5. Timing mechanism as claimed in claim 4 in which the work-controlled means comprises a plate rotatable about the first shaft and adjacent a wall of the casing, balls carried in the openings in the plate, normally seated in depressions in the wall of the casing and in engagement with said flanged disk, a work-controlled feeler, and means connecting the feeler and the plate to rotate the latter to cause the balls to ride up and out of the depressions and shift the flanged disk in a direction to cause its flange to over-lie the tail of the lever.
